VANITY ATTACHMENT KIT FOR CAR VISORS

Herbert S. Chase, Flushing, N. Y.

Application May 23, 1956, Serial No. 41,617

Term of patent 7 years

(Cl. D86—10)

Fig. 1.

Fig. 2.

Fig. 3.

Fig. 1 is a perspective view of a vanity attachment kit for car visors showing my new design;

Fig. 2 is an end view of the same; and

Fig. 3 is a rear view of the same.

I claim:

The ornamental design for a vanity attachment kit for car visors, substantially as shown.
